(57) **CLAIM**

The ornamental design for a stretcher structure used in
multiple collapsible umbrella, as shown.

DESCRIPTION

FIG. 1 is a perspective view of the stretcher structure used
in multiple collapsible umbrella of this invention;
FIG. 2 is a front view thereof;
FIG. 3 is a rear view thereof;
FIG. 4 is a left view thereof;
FIG. 5 is a right view thereof;
FIG. 6 is a top view thereof; and,
FIG. 7 is a bottom view thereof.
